THREAD PULL-OFF MECHANISM FOR
SEWING MACHINES

Alfred R. Wood, Bridgeport, Conn., assignor to
The Singer Manufacturing Company, Elizabeth, N. J., a corporation of New Jersey

Application August 21, 1945, Serial No. 611,724

10 Claims. (Cl. 112—242)

1

This invention relates to buttonhole sewing machines, more particularly of the automatic lock-stitch "straight" type, which is adapted to produce high quality buttonholes used most commonly in men's shirts, collars, cuffs and the like.

The type of stitch used to form this high quality buttonhole is generally referred to in the trade as the pyramid-purl lock-stitch. In this type of stitch-formation, the needle-thread take-up is required not only to draw up the needle-thread loops after they have been interlocked with the bobbin-thread, but also to draw such loops entirely through the work, pulling loops of bobbin-thread through to the upper side of the work, so that in the finished seam the needle-thread will lie in substantially a straight line intermediate the rows of zigzag needle-punctures, while loops of bobbin-thread emerge from the needle-punctures at the upper side of the work and embrace the straight needle-thread. To effect this stitch-formation, it is necessary that the tension imposed upon the bobbin-thread be light, while the tension imposed upon the needle-thread be very strong. To further assist in properly concatenating the needle- and bobbin-threads, it has been common to employ a bobbin-thread pull-off mechanism, which is designed to operate once during each stitch-forming cycle to pull from the bobbin a length of thread to be absorbed into the stitch when the needle-thread loop is pulled up by the usual take-up. The presence of this slack bobbin-thread available after the pull-off member is retracted permits a reduction in the amount of tension required on the needle-thread. This is advantageous inasmuch as it minimizes thread breakage.

The successful operation of the bobbin-thread pull-off is materially affected by the inherent elasticity of the thread being used. The effect of using a bobbin-thread having considerable elasticity, or one in which the elasticity varies somewhat throughout its length, is that unequal lengths of thread are pulled from the bobbin during the formation of the stitches in the buttonhole. The result of a variation in the length of thread pulled off is that, in the finished buttonhole, the needle-thread lies in a line which is wavy relative to the buttonhole slit. This defect is immediately discernible to the naked eye and therefore materially reduces the quality of the finished buttonhole.

Therefore, it is the primary object of the present invention to provide an improved pull-off

2

mechanism which is effective to draw a uniform length of bobbin-thread from the supply during each stitch-forming cycle, whereby a finished buttonhole is produced having the pyramid-purl formed in a straight line substantially parallel to and uniformly spaced from the buttonhole slit.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings:

Fig. 1 represents a front elevational view, partly in section, of a buttonhole machine equipped with my improved bobbin-thread pull-off mechanism.

Fig. 2 represents a bottom plan view, partly in section, showing the connections for actuating the pull-off blade.

Fig. 3 represents a vertical sectional view taken substantially along the line 3—3, Fig. 1, illustrating the mechanical opener mechanism for the loop-taker and also the means employed for rendering the thread pull-off blade ineffective.

Fig. 4 represents a fragmentary view of a buttonhole, showing the manner in which the needle-thread and bobbin thread are concatenated to form a pyramid-purl.

Fig. 5 represents a vertical sectional view taken substantially along the line 5—5, Fig. 3.

Fig. 6 represents an enlarged top plan view of the loop-taker thread-case and carrier therefor, showing the desired shape of the rotation-restraining member and the leaf-spring by which the bobbin-thread is maintained in position in said rotation-restraining member.

Fig. 7 represents an enlarged left side elevational view, partly in section, of the C-shaped thread-guiding projection on the thread-case between the spaced limbs of which operates the bobbin-thread pull-off blade.

Fig. 8 represents a sectional view taken substantially along the line 8—8, Fig. 3.

Fig. 9 represents a right side elevational view, partly in section, of the stitch-forming instrumentalities, showing the bobbin-thread pull-off blade in its maximum thread pull-off position.

Fig. 10 is a view similar to Fig. 9, but with the pull-off blade shifted laterally to its ineffective position, in which position the blade is out of

the range of the lead of the bobbin-thread between the spaced limbs of the C-shaped thread-guiding projection on the thread-case.

Referring to the drawings, the machine chosen for the purposes of the present disclosure is constructed substantially in accordance with that forming the subject of my United States Patent No. 2,411,493, issued November 19, 1946, and has a frame including a bed 11 provided with a supporting lug 12. Journaled in a bushing 13 pressed into the supporting lug 12 is a rotary loop-taker shaft 14 geared to be operated by an arm-shaft (not shown) at a speed twice that of the arm-shaft. As clearly shown in my above mentioned patent, the arm-shaft is connected at the head-end of the machine to endwise reciprocate a thread-carrying needle 15 which is adapted to be vibrated in a direction crosswise of the bed 11. Cooperating with the needle 15 in the formation of lock-stitches is a loop-taker, indicated generally as 16, of the rotary lock-stitch type, which loop-taker is fast on the rotary shaft 14.

The work to be buttonholed is adapted to be held in a work-clamp comprising the usual lower work-plate 17 and the upper clamp-foot 18, Fig. 1. The work-clamp is slowly moved in step-by-step fashion under the endwise reciprocatory and laterally vibratory needle 15, and relative to the usual needle-aperture 19 in the throat-plate 20, first away from the machine-standard and then towards the machine-standard to cause the first and second rows of side zigzag stitches to be laid side by side in the work. The work-clamp derives its step-by-step movements from the usual feed-cam 21 through a link 22, Fig. 2, connected at one end to a slide-block 23 associated with the lower work-plate 17 and operable in a slideway 24 provided in the bed 11.

As previously mentioned, the stitch-forming mechanism of the machine illustrated comprises the endwise reciprocatory and laterally vibratory thread-carrying needle 15 and the supplemental rotary hook 16. The rotary hook is adapted to seize the thread-loop presented by the needle and expand such loop for passage about the under thread-mass contained in the stationary thread-mass enclosing means of the rotary hook. The thread-mass enclosing means shown in the drawings forms the subject of my United States Patent No. 2,419,698, dated April 29, 1947, and therefore only sufficient reference will be made in this case to this means as will be required to give an understanding of the operation of the bobbin-thread pull-off. Suffice it to say that the thread-mass enclosing means comprises a cup-shaped carrier-member 25 and a telescopically disposed thread-case 26, defining between them a thread-mass cavity into which is inserted the usual bobbin or cop. To restrain the thread-mass enclosing means against rotation with the rotary loop-seizing beak of the loop-taker, the carrier-member 25 has extending upwardly from its periphery a substantially C-shaped projection 27, the upper portion of which is adapted to extend between the free ends of a pair of stop-plates 28 and 29 (Fig. 1), adjustably secured to the bed 11 of the machine-frame. The C-shaped projection 27 is vertically channeled to receive a correspondingly shaped upstanding projection 30 formed on the thread-case 26.

As fully disclosed in my above mentioned U. S. Patent No. 2,419,698 and shown in Figs. 9 and 10 of this case, the bobbin-thread emerging from the usual thread-aperture in the thread-case 26 is directed beneath a tension-spring 31, then be-

hind a thread-guiding pin 32, upwardly through a threading-slit 33 provided in the thread-case projection 30, and thence beneath the free end of a leaf-spring 34 fastened to the upper limb 35 of the projection 30. As will be seen in Figs. 9 and 10, the thread-guiding pin 32 and the leaf-spring 34 function to maintain the bobbin-thread adjacent the inner end of the threading-slit 33, which position of the thread is advantageous as regards the successful operation of the bobbin-thread pull-off now to be described. Also, the leaf-spring 34 serves to lightly nip the bobbin-thread and thus prevent the accidental unthreading of the upper limb 35.

Disposed to operate between the spaced bobbin-thread-directing guides defined by the upper and lower limbs 35 and 36 of the C-shaped projection 30 is a curved thread pull-off blade 37 having a thread-cam edge 38 formed adjacent its free end. At its other end, the pull-off blade 37 merges into an offset shank 39 (Fig. 3) provided with an elongated hole 40 and an inturned positioning lip 41; the lip being adapted to enter a slot 42 formed in the outer end of a carrier-lever 43 which embraces and is freely journaled at its inner end on the exposed end of the hook-shaft bushing 13. A clamp screw 44 passing through the elongated hole 40 and threaded into the carrier-lever 43 adjustably secures the blade 37 to said lever 43. The lip 41, when disposed in the slot 42, prevents the pull-off blade 37 from turning about the clamping screw 44. As the carrier-lever 43 is actuated to fulcrum on the periphery of the hook-shaft bushing 13, the pull-off blade 37 moves into and out of thread-engaging position between the limbs 35 and 36 of the C-shaped projection 30. When the pull-off blade 37 is advanced from its retracted position, shown in full lines in Fig. 5, to its advanced position, shown in dotted lines in the same figure, the thread-cam edge 38 is adapted to contact and deflect laterally the portion of the bobbin-thread leading from the lower to the upper limb of the C-shaped projection 30 and form a bight in the thread between the limbs of the projection, in the manner shown in Fig. 9. The blade 37, in forming the bight in the bobbin-thread, draws from the supply within the thread-case 26 a length of thread sufficient to form a bobbin-thread loop of a size such that it may be pulled through to the upper side of the work (Fig. 4), so that in the finished seam the needle-thread will lie in substantially a straight line adjacent the buttonhole slit. It will be noted that the limbs 35 and 36 of the C-shaped projection 30 are rather closely spaced apart. This is advantageous for the reason that the bobbin-thread extending between the limbs 35 and 36, as shown in dotted lines in Fig. 9, is relatively short. It is, in fact, so short that, when the thread-cam edge 38 of the pull-off blade engages the thread, any inherent elasticity in the thread does not militate against the drawing of a uniform length of thread from the supply during each stroke of the pull-off blade.

The mechanism for actuating the bobbin-thread pull-off blade 37 preferably comprises a counterbalanced crank 45 (Fig. 5) having a crank-pin 46 connected by a link 47 to a pin 48 threaded into the carrier-lever 43. The counterbalanced crank 45 is carried on the outer end of a horizontally disposed rotary actuating shaft 49 journaled in a bearing bushing 50 pressed into the supporting lug 12. Secured on the other end of the actuating shaft 49 is a gear 51 in mesh with a

half-size gear 52 fast on the hook-shaft 14. Through the mechanism just described, rotation of the hook-shaft 14 imparts to the actuating shaft 49, through the gearing 51 and 52, rotary movements at one half the speed of the hook-shaft. In other words, the pull-off blade 37 is given one complete to-and-fro actuation for each stitch-forming cycle. As the actuating shaft is rotated, the counterbalanced crank 45 imparts to the carrier-lever 43, through the link 47 and pin 48, a motion causing the carrier-lever to oscillate about the bushing 13. The pull-off blade 37, which is secured to the carrier-lever, is thereby swung about an axis coaxially with the rotary hook 16 and is timed to begin its advance as the needle is starting down and to complete its advance at about the time the needle reaches the limit of its downstroke. The pull-off blade 37 dwells in its advanced position (dotted lines in Fig. 5) while the needle is throwing out a loop of upper thread for seizure by the rotary hook 16. The pull-off then retracts so that slack bobbin-thread is available to be absorbed into the next stitch when the needle-loop is pulled up by the usual needle-thread take-up mechanism. At the time of initial engagement of the pull-off blade 37 with the bobbin-thread, said blade is moving at a speed considerably less than that of the rotary hook 16. This fact, coupled with the gradual incline of the thread-cam edge 38, results in the pull-off blade engaging the bobbin-thread with a smooth action, thus avoiding a jerking of the bobbin-thread and minimizing any tendency toward overrunning or spilling of thread by the bobbin or cop.

Provision is made for rendering the pull-off blade 37 ineffective during the sewing of the barring stitches at each end of the buttonhole so that the locking points of these stitches will not be pulled through the work as are the side stitches of the buttonhole. To this end, the working position of the carrier-lever 43 is shifted longitudinally of the bushing 13 so that the free end of the pull-off blade will, in its advance, miss the bobbin-thread, as shown in Fig. 10. To effect this shifting of the pull-off blade 37, the hub of the carrier-lever 43 is formed with a circumferential groove 53 which is entered by the half-round recessed portion of an arm 54 (Fig. 8) on a slide-shaft 55 journaled in the supporting lug 12. At its rearward end, the slide-shaft 55 has adjustably fastened on it a head 56 adapted to be contacted by a roller 57 journaled on the free end of a horizontally disposed swing-lever 58 pivoted on a stud 59 threaded into the bed 11. The lever 58, at its free end, is longitudinally recessed, as at 60, to adjustably receive a cam-follower 61 having an elongated aperture 62 through which passes a clamping screw 63 threaded into the lever 58. The cam-follower is disposed to be engaged by a cam-section 64 secured by screws 64' on the feed-cam 21. While only one cam-section is shown, it will be understood that two cam-sections are employed, one for each barring operation. In the operation of the machine, the feed-cam is rotated in the direction of the arrow in Fig. 2, once during each complete buttonholing cycle. When the cam-section 64 on the feed-cam 21 engages the cam-follower 61, the swing-lever 58 is moved in a direction away from the feed-cam, causing the roller 57 to move into engagement with the head 56 of the slide-shaft 55 and shift the same outwardly against the action of a coil-spring 65 acting between a collar 66 on the slide-shaft and the supporting lug 12. When

the slide-shaft 55 is shifted, the carrier-lever 43, through the medium of the arm 54, is moved outwardly on the bearing bushing 13 and to the extent that the point of the pull-off blade 37 entirely misses the bobbin-thread (Fig. 10) and no bobbin-thread is pulled off during the formation of the barring stitches. After the completion of the last barring stitch and the cam-section 64 has moved beyond the cam-follower 61, the coil-spring 65 acts to return the pull-off blade 37 to its effective position, which position is determined by the hub of the arm 54 striking the supporting lug 12. As shown in Fig. 3, the pin 48 slides relative to the upper end of the link 47 during the shifting of the pull-off blade and, consequently, the driving relationship of the pull-off blade actuating mechanism is not interrupted. It will be understood that the timing of the shaft of the pull-off blade from effective to ineffective position 20 can be regulated by virtue of the adjustment of the cam-follower 61 on the swing-lever 58. Moreover, the ineffective position of the pull-off blade can be accurately determined by adjusting the head 56 lengthwise of the slide-shaft 55.

As mentioned above, the bobbin supply is adapted to be housed in a thread-mass enclosing means including a thread-case 26 and a carrier 25 therefor; the thread-case and carrier being restrained against rotation with the rotary loop-taker 16 by means of the loosely interengaging projection 27 and stop-plates 28 and 29. The thread-case and its carrier have a normal tendency to rotate with the loop-taker, thereby causing the rotation-restraining projection 27 to bear 30 against one of the stop-plates. In order to obtain a free passage on each side of the projection 27 for the unobstructed free travel of the needle-thread loop about the thread-case and its carrier during stitch-formation, the thread-case 30 and its carrier are intermittently oscillated, for a limited extent, in a direction opposite to the direction of rotation of the loop-taker. This oscillation is effected by means of a mechanical opener which forms the subject of my divisional 40 application Serial No. 678,618, filed June 22, 1946, and comprises an opener-arm 67 (Figs. 1 and 3) which is adjustably clamped at its lower end in a split socket-member 68 fast on the outer end of a rock-shaft 69 journaled in a horizontal bushing 70 pressed into the supporting lug 12. At its upper end, the opener-arm 67 is bent, as at 71, to provide a hook-shaped end extending toward the thread-case 26; the hook-shaped end being notched, as at 72, Fig. 1, to form spaced resilient 50 fingers 73 adapted to enter an opener-arm receiving pocket 74 formed in the thread-case carrier 25 on the cast-on side thereof. The fingers 73 are preferably shaped so that there is a smooth cam-like initial engagement of the upper finger with one side of the thread-case carrier pocket 74 to initiate an oscillation of the thread-case carrier 25 in a direction reverse to the direction of rotation of the hook-body, and that following this engagement the lower finger yieldingly engages the other side of the pocket 74, whereby the rotation-restraining projection 27 is maintained stationary substantially midway between the stop-plates 28 and 29. The spaced resilient 60 fingers 73 serve to provide a relatively noiseless mechanical opener, as well as one which maintains the rotation-restraining projection on the thread-mass enclosing means stationary and in position such that an open thread passage exists on both sides of the projection for the free unobstructed travel of the needle-thread loop.

The opener-arm rock-shaft 69 is actuated by means of a rock-lever 75 which is connected to one end of a short pitman 76 embracing at its other end an eccentric 77 preferably integral with the gear 51. Separating the pitman 76 from the end of the bushing 50 is a disk 78 secured to the eccentric 77 by a screw 79 (Fig. 3).

From the above description taken in connection with the accompanying drawings, it will be understood that I have invented a bobbin-thread pull-off mechanism which is accurate in its operation, drawing from the supply an equal length of thread during each stitch-forming cycle, regardless of the degree of elasticity inherent in the thread. The upstanding C-shaped rotation-restraining projection on the thread-case carrier provides closely spaced thread-confining limbs between which operates the thread pull-off blade. In addition, the rotation-restraining projection provides a surface which functions to retard one limb of the needle-thread loop as it is being cast off the thread-case, and this retardation minimizes twisting of the thread comprising the loop, thereby preventing the formation of loops or knots in the pyramid-purl of the buttonhole. Furthermore, since the upper limb 35 of the rotation-restraining projection is positioned adjacent the bottom of the throat-plate 20, the short cut end of the bobbin-thread, which is produced by the actuation of the usual thread-cutting devices following the completing of the buttonhole, is retained by the slight nipping action of the leaf-spring 34 near the work and not permitted to drop down out of control. This control of the bobbin-thread insures the proper operation of the pull-off mechanism on the first stitch of the next buttonholing cycle.

Having thus set forth the nature of the invention what I claim herein is:

1. A sewing machine having, in combination, a thread-carrying reciprocatory needle, a circularly moving loop-taker cooperating therewith, a bobbin-thread-mass enclosing means journaled in said loop-taker, a rotation-restraining projection on said thread-mass enclosing means having a pair of spaced thread-directing guides, and a thread pull-off member adapted to engage the bobbin-thread between said thread-directing guides during each stitch-forming cycle.

2. A sewing machine having, in combination, a thread-carrying reciprocatory needle, a circularly moving loop-taker cooperating therewith in the formation of lock-stitches, a bobbin-thread-mass enclosing means journaled in said loop-taker and restrained against rotation therewith, a projection extending from said bobbin-thread-mass enclosing means and providing a pair of spaced thread-directing guides, and a thread pull-off member arranged to engage the bobbin-thread between said thread-directing guides once during each stitch-forming cycle.

3. A two-thread sewing machine having, in combination, a thread-carrying reciprocatory needle, a rotary loop-taker having a loop-seizing beak cooperating with said needle in the formation of lock-stitches, a bobbin-thread-mass enclosing means journaled in said loop-taker and restrained against circular movement therewith, a pair of bobbin-thread-directing guides disposed outside the field of action of the loop-seizing beak of said rotary loop-taker, and a thread pull-off member arranged to engage the bobbin-thread between said thread-directing guides to draw thread from the bobbin once during each stitch-forming cycle.

4. A two-thread sewing machine having, in combination, a thread-carrying reciprocatory needle, a circularly moving loop-taker having a loop-seizing beak cooperating with said needle in the formation of lock-stitches, a bobbin-thread-mass enclosing means journaled in said loop-taker and restrained against rotation therewith, said bobbin-thread-mass enclosing means including a thread-case having a cylindrical side wall, a projection extending from said thread-case and providing a pair of spaced limbs disposed beyond the confines of said cylindrical side wall, a thread-directing guide in each of said limbs, and a thread pull-off member adapted to engage the bobbin-thread between said thread-directing guides once during each stitch-forming cycle.

5. A sewing machine having, in combination, a thread-carrying reciprocatory needle, a circularly moving loop-taker cooperating therewith in the formation of lock-stitches, a bobbin-thread-mass enclosing means journaled in said loop-taker, a rotation-restraining projection on said bobbin-thread-mass enclosing means terminating in substantially C-shape at its free end, thereby defining a pair of spaced limbs each having a thread-directing guide, and a thread pull-off member adapted to engage the bobbin-thread between said thread-directing guides to draw thread from the bobbin once during each stitch-forming cycle.

6. A sewing machine having, in combination, a bed fitted with a throat-plate, a thread-carrying reciprocatory needle, a circularly moving loop-taker cooperating with said needle in the formation of lock-stitches, a bobbin-thread-mass enclosing means journaled in said loop-taker and restrained against circular movement therewith, a first bobbin-thread directing guide disposed adjacent said throat-plate, means for preventing the accidental unthreading of said first thread-directing guide, a second bobbin-thread-directing guide spaced from said first bobbin-thread-directing guide, and a thread pull-off member arranged to engage the bobbin-thread between said first and second bobbin-thread-directing guides to draw thread from the bobbin once during each stitch-forming cycle.

7. A sewing machine having, in combination, a bed fitted with a throat-plate, a thread-carrying reciprocatory needle, a circularly moving loop-taker cooperating with said needle in the formation of lock-stitches, a bobbin-thread-mass enclosing means journaled in said loop-taker and restrained against circular movement therewith, a first bobbin-thread directing guide disposed adjacent said throat-plate, a leaf-spring cooperating with said first thread-directing guide for preventing accidental unthreading of said guide, a second bobbin-thread-directing guide spaced from said first bobbin-thread-directing guide, and a thread pull-off member arranged to engage the bobbin-thread between said first and second bobbin-thread-directing guides to draw thread from the bobbin once during each stitch-forming cycle.

8. A sewing machine having, in combination, a bed having a throat-plate, means providing a rotation-restraining notch positioned adjacent said throat-plate, a thread-carrying reciprocatory needle, a circularly moving loop-taker having a loop-seizing beak cooperating with said needle in the formation of lock-stitches, a bobbin-thread-mass enclosing means journaled in said loop-taker, a rotation-restraining projection on

said bobbin-thread-mass enclosing means and disposed to enter the notch adjacent said throat-plate, a first thread-directing guide provided on said rotation-restraining projection adjacent said throat-plate, a second thread-directing guide on said projection spaced from said first thread-directing guide, and a thread pull-off member adapted to engage the thread intermediate the first and second thread-directing guides.

9. A sewing machine having, in combination, a thread-carrying reciprocatory needle, a circularly moving loop-taker cooperating therewith in the formation of lock-stitches, a bobbin-thread-mass enclosing means journaled in said loop-taker, a rotation-restraining projection on said bobbin-thread-mass enclosing means and having spaced limbs, an open-sided threading-slit cut into said spaced limbs so that the closed end of the threading-slit is adjacent the ends of the limbs, means for maintaining the bobbin-thread adjacent the closed end of said threading-slit, thereby to provide spaced bobbin-thread-directing guides, and a thread pull-off member adapted to engage the bobbin-thread between the limbs of said rotation-restraining projection.

10. A sewing machine having, in combination, a thread-carrying reciprocatory needle, a rotary loop-taker cooperating therewith in the forma-

tion of lock-stitches, a bobbin-thread-mass enclosing means journaled in said loop-taker, a rotation-restraining projection on said bobbin-thread-mass enclosing means terminating in substantially C-shape at its free end to provide spaced limbs, an open-sided threading-slit formed longitudinally of said limbs and ending short of the ends of said limbs, means associated with each of the limbs for maintaining the thread in the closed end of said threading-slit, and a thread pull-off member adapted for engaging the thread between the limbs of the rotation-restraining projection.
